Bernard Schiffman, New York, N. Y.

Application September 8, 1953, Serial No. 26,728

Term of patent 14 years

(Cl. D14—6)

Fig. 1.

Fig. 2.

To all whom it may concern:

Be it known that I, Bernard Schiffman, have invented a new, original, and ornamental Design for an Automobile Crib, of which the following is a specification, reference being had to the accompanying drawing, forming a part hereof.

Figure 1 is a perspective view of an automobile crib embodying my new design; and

Figure 2 is a side view thereof.

The front and rear automobile seats disclosed in broken lines are shown only for purposes of illustration. The criss-cross pattern represents quilted padding.

I claim:

The ornamental design for an automobile crib, as shown and described.
